UNITED STATES PATENT OFFICE.

EMMET PROBST, OF PATERSON, NEW JERSEY.

SHADE-ROLLER BRACKET.

1,115,020.

Specification of Letters Patent. Patented Oct. 27, 1914.

Application filed May 5, 1914. Serial No. 836,438.

To all whom it may concern:

Be it known that I, EMMET PROBST, a citizen of the United States, residing at Paterson, in the county of Passaic and State of New Jersey, have invented certain new and useful Improvements in Shade-Roller Brackets, of which the following is a specification.

This invention relates to shade roller brackets of the class designed to permit adjustment so as to accommodate shade rollers varying in length and it consists in certain improvements whereby a fixture of this character may be manufactured at a minimum cost, will present a neat and attractive appearance when in place and will be simple in construction and require the simplest operations to adjust it.

In the accompanying drawing, Figure 1 shows a window frame and a shade supported therein by my improved adjustable shade roller brackets; Figs. 2 to 5 illustrate the improved bracket as formed from sheet material, Fig. 2 showing the blank from which the supporting member of the bracket is formed, Fig. 3 being a front elevation of the supporting member, Fig. 4 a perspective view of the supporting member and bracket proper assembled, the former appearing in section, and Fig. 5 is a plan view of the supporting member and bracket assembled and attached to the woodwork; and, Figs. 6 and 7 show a modification in which the supporting member is formed of relatively thick material, Fig. 6 being a perspective view of said supporting member and Fig. 7 the bracket proper adapted to the supporting member shown in Fig. 6.

Referring first to Figs. 2 to 5, *a* is an elongated blank of sheet metal having at both ends and on both sides the rectangular wings *b*. This blank is placed in a suitable press and shaped as follows: The wings *b* are bent all in the same direction so as to stand at right angles to the plane of the body of the blank, thereby forming rests *c* (Figs. 4 and 5) which, when placed against a supporting surface, as that of the window frame *d*, will space the body of the blank from said surface. Transverse parallel and

equidistant folds *e* are also formed in the blank, preferably all upstanding from the inside thereof, and forming ribs the same producing the recesses *f*. Further, holes *g* are formed to receive screws *h* for attaching to the woodwork the supporting member which has thus been formed.

The bracket proper consists of a piece of sheet metal stamped to form an arm *i* suitably shaped to receive the trunnions of the shade roller, and the inverted U-shaped clip *j* having a locking lug *k*.

Referring to Figs. 6 and 7, the supporting member *l* is a solid piece of (preferably cast) metal having transverse grooves *m* formed therein and producing the recesses like the recesses *f* already described and also having holes *n* to receive attaching screws. The bracket proper *o* is substantially the same as the bracket proper already described excepting that its clip *p* is made sufficiently wide to fit over the supporting member *l*.

When the brackets proper, marked *A* in Fig. 1, are supporting the shade roller, marked *B* in said figure, the inverted U-shaped straps thereof straddle the supporting members, marked *C* in Fig. 1, and engage in their recesses, fitting snugly therein so that there is no lost motion; their locking lugs *k* (or *q* in Fig. 7) engage the under sides of the supporting members *c*, so that the brackets proper are held against working up and off the supporting members. To remove a bracket proper it is only necessary to spring open more or less its clip until the locking lug clears the supporting member. For adjusting the bracket to suit different lengths of shade rollers it will be understood that the bracket proper is shifted from one to another recess.

In the preferred form of the invention, the U-shaped clip exerts clamping pressure on the supporting member, so that there is no lost motion between the parts.

Having thus fully described my invention, what I claim as new and desire to secure by Letters Patent is:—

In combination, an elongated supporting member adapted to be secured horizontally

to the wood-work, and a bracket proper having an elastic inverted U-shaped clip straddling the supporting member and having on one of the U-shape forming extremities 5 thereof a locking lug engaging the under side of said member, substantially as described.

In testimony whereof I affix my signature in presence of two witnesses.

EMMET PROBST.
